Inventor

Henry C. Hachmuth

UNITED STATES PATENT OFFICE

HENRY C. HACHMUTH, OF COMSTOCK PARK, MICHIGAN

STEPLADDER

Application filed January 21, 1929. Serial No. 333,792.

This invention relates to step ladders and its object is to provide a step ladder having legs which will move about relative to each other and readily accommodate their positions to an uneven surface on which the ladder is supported and will support the ladder on such an uneven surface rigidly and without fear of tipping. This ladder is primarily intended for use in orchards and other places 10 out of doors, on hillsides or rough uneven ground but it is equally adaptable for use in other places and in any place where a step ladder of any kind may be used.

The invention embodies various new and 15 useful features of construction and arrangement as hereinafter more fully described and particularly pointed out in the claims, reference being had to the accompanying drawing, in which,

20 Fig. 1 is a perspective view of a step ladder embodying this invention and showing the essential features of construction.

Fig. 2 is a front view of the upper end of the step ladder.

25 Fig. 3 is a side view of the same, and

Fig. 4 is an enlarged rear view of the swinging rear leg supporting structure removed from the ladder and with the lower portion broken away.

30 Like numbers refer to like parts in all figures.

The ladder embodying this invention has conventional front leg and step construction 1 to the upper end of which is attached the usual broad top step or ladder top 2. The two front legs are spaced apart and the steps of the ladder extend between them in conventional form and the top 2 is preferably attached to the upper ends of the front legs 40 by means of angle plates 3 secured by suitable fastening means such as bolts or rivets 12 and 13.

A supporting plate 6 is located closely beneath the ladder top 2 near the rear edge 45 thereof and is pivotally connected by bolts or other suitable pivot means 14 to the angle plates 3 so that it will swing on a horizontal axis. This supporting plate 6 carries the adjustable rear legs 4 of the ladder. A vertical shaft 11 extends through the central portion

of the supporting plate 6 and is rotatable in the plate on a substantially vertical axis at all times perpendicular to the axis of the pivots 14 of the plates 6. The plate 6 is preferably formed of sheet metal and has flanges 55 turned at right angles to it at its upper and lower edges and at its ends and the end flanges serve as means through which the pivots 14 extend and the upper and lower flanges provide portions through which the shaft 11 extends. Other structures may be utilized in this respect and the sheet metal construction shown is not important to the invention.

The lower portion of the shaft 11 below the supporting plate 6 is provided with oppositely extending ears 8 and the two rear legs 4 are respectively pivotally connected at their upper ends to each of said ears 8. Below the ears 8 and centrally located with the axis of the shaft 11, a stud 17 extends at right angles 65 to the axis of said shaft and a lever 10, forming a part of an equalizing device, is pivoted mid-way between its ends on the stud 17. Each end of the lever 10 has a link 9 pivotally attached to it and the opposite end of each link 9 is pivotally connected by a bolt or stud 18 to a respective leg 4 at a point spaced below its pivotal connection with an ear 8. In the specific construction shown a square elongated block 5 is provided with an axial opening 70 to receive the lower end of the shaft 11, which shaft is held in place in the block 5 by the stud 17 which extends through it and the upper end of the block serves as a shoulder to engage the lower surface of the supporting plate 6. The ears 8 are in the form of plates applied to opposite sides of the block 6 by fastening means 15 and the upper ends of the legs 4 lie, and are pivoted between 75 the two plates 8. This specific construction, however, is not essential and any structure providing the shaft 11 with a shoulder to engage the lower surface of the plate 6 and having ears to which the upper ends of the legs 4 may be pivotally attached and a stud 17 will properly function.

The upper end of the shaft 11 is provided with a retaining means such as a cotter pin 10 extending through it to retain it in place in the supporting plate 6.

This structure permits the lower ends of the rear legs 4 to be spread apart at will and the leveling device comprising the lever 10 and the links 9 causes them to move uniformly with respect to the axis of the shaft 11. The shaft 11 will pivot in the supporting plate 6 on an axis perpendicular to the pivots 14 and the supporting plate 6 will swing relative to the front legs of the ladder and its top on said pivots 14. By this arrangement the user may place the front legs of the ladder upon the ground or supporting surface in the desired location irrespective of the unevenness of the surface and tip the ladder backward to the desired angle and then spread the rear legs 4 and turn them about the axis of the shaft 11 and swing them about the pivots 14 until they automatically find a firm engagement with the ground and this universal pivoting and swinging and mounting of the rear legs permits them to firmly engage the ground regardless of its uneven surface.

I claim:

1. A step ladder comprising a front leg structure, a rear leg structure, a supporting plate pivotally connected to the upper end of the front leg structure to swing on a horizontal axis and means for mounting the rear leg structure on said supporting plate to turn on an axis substantially perpendicular to the support on which the leg structures of the step ladder rest.

2. A step ladder comprising a front leg structure, a supporting plate pivoted on a horizontal axis to the upper end of said front leg structure, a mounting bracket pivotally connected to said supporting plate on an axis perpendicular to said horizontal axis of said supporting plate, two rear legs pivotally connected at their upper ends to said mounting bracket and an evener associated with said mounting bracket and said rear legs causing the legs to swing uniformly relative to the perpendicular axis of the mounting bracket.

3. A step ladder comprising a front leg structure, a supporting plate pivoted on a horizontal axis to the upper end of said front leg structure, a mounting bracket pivotally mounted on said supporting plate on an axis perpendicular to the horizontal axis of the plate, two rear legs pivotally connected at their upper ends to said mounting bracket, a lever pivotally connected between its ends to said mounting bracket, and a link pivotally connected to each end of said lever, each link being also pivotally connected to a respective rear leg.

4. A step ladder comprising a front leg structure, a rear leg structure, a supporting plate movably connected to the upper end of the front leg structure and means for mounting the rear leg structure on said supporting plate to turn about an axis substantially perpendicular to the support on which the leg structures of the step ladder rest.

5. A step ladder comprising a front leg structure, a supporting plate pivoted on a horizontal axis to the upper end of said front leg structure, means pivotally connected to said supporting plate on an axis perpendicular to said horizontal axis of said supporting plate, two rear legs pivotally connected at their upper ends to said means and an evener associated with said means and said rear legs for causing the legs to swing uniformly relative to the perpendicular axis of the said means.

HENRY C. HACHMUTH.
